UNITED STATES PATENT OFFICE

171,171

PAIR OF SPECTACLES

Arthur R. Suma, Sr., Chicago, Ill.

Application August 14, 1953, Serial No. 26,454

Term of patent 7 years

(Cl. D57—1)

To all whom it may concern:

Be it known that I, Arthur R. Suma, Sr., a citizen of the United States of America, residing at Chicago, Illinois, have invented a new, original, and ornamental Design for a Pair of Spectacles, of which the following is a specification, reference being had to the accompanying drawing, forming a part hereof.

In the drawing, Fig. 1 is a front elevational view of a pair of spectacles showing my new design;

Fig. 2 is a rear elevational view thereof;

Fig. 3 is a side elevational view with the temples open;

Fig. 4 is a top view thereof, and Fig. 5 is a bottom view thereof.

I claim:

The ornamental design for a pair of spectacles, substantially as shown.

ARTHUR R. SUMA, SR.
